FIG. 1

FIG. 1

FIG. 2

FIG. 3

FIG. 1 is a top plan view of a sheet material showing my new design, said view being fragmentarily shown to indicate indeterminate width and length and it is understood that the repeat pattern continues uniformly throughout its length and width;

FIG. 2 is a fragmentary portion of the top plan view of FIG. 1 on an enlarged scale;

FIG. 3 is a fragmentary vertical sectional view on an enlarged scale taken along line 3-3 of FIG. 2; and

FIG. 4 is a fragmentary vertical sectional view on an enlarged scale taken along line 4-4 of FIG. 2.

The undisclosed bottom is substantially flat and unornamented.

I claim:

The ornamental design for sheet material, substantially as shown and described.
